[57] CLAIM

The ornamental design for a dental material dispenser,
substantially as shown.

DESCRIPTION

FIG. 1 is an oblique, left-front, perspective view of a
dental material dispenser showing my new design;
FIG. 2 is a top plan view thereof;
FIG. 3 is a left side elevational view thereof with the
opposite side being substantially the same;
FIG. 4 is a rear elevational view thereof; and
FIG. 5 is a bottom plan view thereof.
